UNITED STATES PATENT OFFICE.

ALBERT G. ELVIN, OF SOMERVILLE, NEW JERSEY, AND FREDERICK W. MARTIN, OF NEW YORK, N. Y.; SAID MARTIN ASSIGNOR TO SAID ELVIN.

PEDAL DEVICE FOR FIRE-DOORS.

1,148,581.

Specification of Letters Patent.

Patented Aug. 3, 1915.

Application filed November 13, 1913. Serial No. 800,731.

To all whom it may concern:

Be it known that we, ALBERT G. ELVIN and FREDERICK W. MARTIN, both citizens of the United States, and residents, respectively, of Somerville, in the county of Somerset and State of New Jersey, and the borough of Manhattan, in the city, county, and State of New York, have invented a certain new and useful Improvement in Pedal Devices for Fire-Doors, of which improvement the following is a specification.

This invention relates to apparatus for controlling the operation of furnace doors, and more particularly the fire doors of a locomotive boiler, the principal object being to provide an improved pedal device having adjustable members whereby the same may be readily applied to different types of existing locomotives, and be easily operated by the foot of the fireman to open the controlling valve of a fluid pressure apparatus for actuating the fire door.

The improvement claimed is hereinafter fully set forth.

25 In the accompanying drawings: Figure 1 is a front elevation of one form of locomotive fire door apparatus embodying our improvement; Fig. 2, a side view of the pedal device with a part shown in vertical section; Fig. 3, a similar view showing a modification in which the length of the lever arm is adjustable; Fig. 4, a detail view of the swivel joint, partly in section; Fig. 5, a detail view of the end of the 30 clamping portion of the lever arm; and Figs. 6 and 7, a plan and side view, respectively, partly in section, and showing a modification.

According to the construction shown, the 40 improvement is exemplified as applied in connection with a fluid pressure apparatus for operating the fire doors of a locomotive boiler, which is illustrated in Fig. 1, as comprising a cylinder, 8, containing a piston for actuating the doors, 9, and a valve casing, 10, containing a valve for controlling the admission of fluid to the pipe, 11, and the cylinder. The valve casing is mounted on, or formed integral with, a casting, 13, supported on a bracket, 12, from the door frame or boiler sheet, and having a projecting portion, 14, to which may be pivoted a lever having an arm, 15, adapted to engage and operate the stem, 22, of the valve. The 45 other arm, 18, of the pedal lever extends

down toward the deck of the locomotive, and is provided with a head, 19, having a horizontal opening in which the tread bar, 20, of the tread, 21, is slidably supported. A plurality of notches may be formed in the 60 bar, 20, and a weighted pin, 23, mounted in the head, 19, is adapted to engage with any one of said notches as the tread is adjusted forward or backward to the desired position.

In order that the pedal arm may be laterally adjustable, a swivel joint, 16, may be provided, turning upon vertical pin, 17, the engaging faces of the joint being formed with radial teeth or corrugations, 16^a. 70 There is sufficient clearance beneath the head of the swivel pin, 17, to allow the upper part to be raised far enough to disengage the teeth and rotate the arm laterally to any desired position. When the parts are 75 in place, the teeth or corrugations mesh together and serve to hold the arm in the position to which it is adjusted as the weight of the pedal is sufficient to prevent slipping of the corrugated faces upon each other. 80

On account of the height of the decks of different locomotives, a vertical adjustment may be desirable, and this may be obtained by making the pedal arm of adjustable length, as indicated in Fig. 3, in which the arm is composed of two telescoping sections, 18^a and 18^b, the tapered end of the outer or tubular member, 18^a, being slit and provided with a nut for clamping the members together at the desired position. 85 To prevent the stem member, 18^b, from rotating in the tubular member, 18^a, a pin and slot connection, 18^c, may be employed. 90

In Figs. 6 and 7, a modification is shown, in which the bracket, 13, carrying the valve 95 casing, 10, is provided with a fan shaped projection, 25, having notches at its periphery, and on which is fulcrumed the pedal lever, 18^d, having extension, 24, supported on the bracket and pivoted thereon 100 by means of the pin, 26. The end of the arm, 24, engages the valve stem, 22, for actuating the control valve and this also serves to hold the pivot of the arm in place and prevent its removal unless the valve is 105 taken out. The pedal lever may be adjusted laterally by raising same from a notch and then turning the arm on its pivot to any other notch desired, the opening for the pin, 26, being flared downward to allow 110

for this movement. The pedal lever, 18^d, may be provided with the same adjustable tread and the same vertical adjustment as shown in Fig. 3.

5. The device is readily operated by the fireman by simply pressing the tread with his foot, and thereby turning the pedal lever upon its fulcrum on the bracket, and opening the control valve each time that the fireman desires to deliver a shovel full of coal to the furnace. He may also readily adjust the pedal lever and tread to any position above the deck to suit his convenience.

It will now be seen that we have provided 15 a simple construction of pedal device for fire doors, which may be easily adjusted either vertically, longitudinally, or laterally, to suit different conditions, and may be readily applied to the different existing 20 types of locomotives.

Having now described our invention, what we claim as new and desire to secure by Letters Patent is:

1. In a fire door apparatus, the combination 25 with a support, of a pedal lever fulcrumed thereon for controlling the operation of the door, and having an arm extending into close proximity to the deck, and an adjustable tread carried at the end of said 30 arm.

2. In a fire door apparatus, the combination 35 with a support, of a pedal lever fulcrumed thereon for controlling the operation of the door, and having an arm extending into close proximity to the deck, said arm being laterally adjustable, and a tread carried at the end of said arm.

3. In a fire door apparatus, the combination 40 with a support, of a pedal lever fulcrumed thereon for controlling the operation of the door, and having an arm extending into close proximity to the deck, said arm having a swivel joint for lateral adjustment, and a tread carried at the end 45 of said arm.

4. In a fire door apparatus, the combination 45 with a support, of a pedal lever fulcrumed thereon for controlling the operation of the door, and having an arm ex-

tending into close proximity to the deck, 50 said arm having a swivel joint with engaging corrugated faces and a vertical pin, and a tread carried at the end of said arm.

5. In a fire door apparatus, the combination 55 with a support, of a pedal lever fulcrumed thereon for controlling the operation of the door, and having an arm extending into close proximity to the deck, and a longitudinally adjustable tread slidably mounted on said arm.

6. In a fire door apparatus, the combination 60 with a support, of a pedal lever fulcrumed thereon for controlling the operation of the door, and having an arm extending into close proximity to the deck, said 65 arm having a vertical adjustment, and a tread carried at the end of said arm.

7. In a fire door apparatus, the combination 70 with a support, of a pedal lever fulcrumed thereon for controlling the operation of the door, and having an arm extending into close proximity to the deck, said arm being formed in adjustable sections, and a tread carried at the end of said arm.

8. In a fire door apparatus, the combination 75 with a motor and a control valve therefor, of a supporting bracket, a pedal lever fulcrumed on said bracket for actuating said valve, and having an arm extending down near the deck, and an adjustable tread carried at the lower end of said arm.

9. In a fire door apparatus, the combination 80 with a motor and a control valve therefor, of a supporting bracket, a pedal lever fulcrumed on said bracket for actuating said valve, and having an arm extending down near the deck, said arm being laterally adjustable, and a longitudinally adjustable tread carried at the lower end of 90 said arm.

In testimony whereof we have hereunto set our hands.

ALBERT G. ELVIN.
FREDERICK W. MARTIN.
